HOLDER FOR TARGETS

Verner M. Miller, Minneapolis, Minn.

Application June 10, 1949, Serial No. 88,245

11 Claims. (Cl. 273—102)

1

This application is a continuation in part of my pending application Serial No. 33,593, for Holder for Targets, filed June 17, 1948, and now abandoned.

The object of the invention is to present a holder for targets wherein will be incorporated desirable and improved features and characteristics designed to render the target holder capable of functioning in an efficient manner.

In the accompanying drawing forming a part of this specification,

Fig. 1 is an elevational view, partially in section and partially broken away, of a holder for targets made according to the invention;

Fig. 2 is an enlarged fragmentary side elevational view of an adjustable post of the target holder;

Fig. 3 is a fragmentary side elevational view of said adjustable post as it would appear from the right in Fig. 2;

Fig. 4 is an elevational view of a frame, with appurtenances, of the target holder as it would appear when removed and folded up;

Fig. 5 is an elevational view of the disclosure of Fig. 4 as it would appear from the top of the sheet;

Fig. 6 is a detail sectional view, taken as on line 6—6 in Fig. 5;

Fig. 7 is a detail sectional view disclosing the manner in which leaf springs of the target holder are secured to upright rods of said target holder; and

Fig. 8 is a detail sectional view, taken on line 8—8 in Fig. 1.

With respect to the drawing and the numerals of reference thereon, 10 denotes a longitudinally adjustable post of the target holder, and 11 indicates a frame supported upon said post and detachably retaining a target 12.

The longitudinally adjustable post 10 is constituted in the disclosure as made as upper and lower, telescoping tubular elements, represented 13 and 14, respectively, a clamping member 15 for securing said upper and lower tubular elements in fixed relation, an upper plug 16 press fitted into the upper end of the upper tubular element 13 and integrally or rigidly supporting an externally threaded element 17 situated above said upper tubular element, and a lower plug 18 press fitted into the lower end of the lower tubular element 14 and integrally or rigidly supporting a pointed element 19 to be driven into the ground. The lower plug 18 has cross-sectional dimension less than that of the pointed element 19, and an annular shoulder 20, provided by said

2

pointed element 19 and in surrounding relation to the lower end of said lower plug 18, is engaged against the lower end of the lower tubular element 14. The lower end portion 21 of the upper tubular element 13 is pointed in order that it can be driven into the ground in any instance when it may be desirable to utilize the target holder with the lower tubular element omitted.

The upper telescoping tubular element 13 is snugly slidable in the lower telescoping tubular element 14, and the upper end portion of said lower telescoping tubular element is longitudinally slotted, as at 22. The clamping member 15 is constituted as a strap member 23, surrounding said slotted upper end portion of the lower telescoping tubular element 14 and spot welded at 24 to said lower telescoping tubular element, and a camming lever 25 pivotally supported as at 26, between parallel ears 27, 27 integral or rigid with said strap member. The construction and arrangement will be such that when the camming lever 25 is situated down against the lower telescoping tubular element 14, as in Figs. 1, 2 and 3 of the drawing, the

slotted portion of said lower telescoping tubular element will be confined by the strap member 23 and gripped against the upper telescoping tubular element 13 thus to cause said upper and lower tubular elements to be secured in fixed relation to each other, and also such that when the camming lever 25 is swung away from the lower telescoping tubular element 14 and upwardly, the slotted portion of said lower telescoping tubular element will be released thus to

allow relative longitudinal adjustment of the upper and lower telescoping tubular elements. The adjustable post 10 will be driven into the ground when the target holder is to be applied to use, and the obvious purpose of relative longitudinal adjustment of the upper and lower telescoping elements 13 and 14 is for setting a target, such as 12, at desired elevation, as, for instance, at higher elevation for taller marksmen or at lower elevation for shorter marksmen or when a marksman is to shoot from a kneeling, sitting or lying position.

In the disclosed embodiment of the invention, the frame 11 is constituted as an elongated rectilinear bar 28, adapted to be situated in a horizontal plane when the target holder is applied to use, and spaced apart, upstanding rods 29, 29 supported upon said elongated rectilinear bar in parallel relation to each other and in perpendicular relation to the elongated bar.

The midlength of the elongated bar 28 in-

cludes a threaded opening for removably receiving the externally threaded element 17 upon the upper plug 16. The construction and arrangement desirably can be such that the upper telescoping element 13, together with the upper plug 16 as a unit, can be rotated to cause the externally threaded element 17 to be situated within the threaded opening in the elongated rectilinear bar 28 to extent causing the lower surface of said elongated rectilinear bar to be engaged against the upper end of said upper telescoping element and the upper surface of said upper plug, as in Fig. 1, thus to cause the elongated rectilinear bar to be rigidly supported upon the longitudinally adjustable post 10 in perpendicular relation thereto.

The upstanding rods 29, 29 are disposed at opposite sides of the threaded opening in the elongated bar 28 in equally spaced relation to said threaded opening, and said upstanding rods are pivotally secured, as at 30, to opposite end portions of the elongated rectilinear bar 28. As shown, each end portion of said elongated rectilinear bar 28 includes spaced apart ears 31, 31 aligned with the elongated rectilinear bar and disposed at the opposite sides and outwardly of a shoulder 32 provided by and in perpendicular relation to said elongated rectilinear bar. Each upstanding rod 29 includes a foot or flange 33 upon its inner end disposed in perpendicular relation to the corresponding upstanding rod and situated between the ears 31, 31 at the corresponding end of the elongated rectilinear bar, and the pivot pins 30 pass snugly through openings in the feet or flanges 33. Desirably, each foot or flange will be of width to span the distance between the ears by which supported. The construction and arrangement will be such that the upstanding rods can be swung to collapsed condition, as in Figs. 4 and 5 and in full lines in Fig. 6, or to upright position, as in Fig. 1 and in dotted lines in Fig. 6, and when said upstanding rods are in upright position, surfaces of their inner end portions opposite their feet or flanges will be engaged against the shoulders 32, as in dotted lines in said Fig. 6. Said shoulders 32 constitute stops limiting the extent of inward swinging movement of the upstanding rods 29, 29 from their positions as in Fig. 1 and in dotted lines in Fig. 6, and, desirably, when said upstanding rods are engaged against the shoulders they will be in perpendicular relation to the elongated rectilinear bar 28 and in parallel relation to each other.

Each of the upstanding rods 29 supports a leaf spring 34 disposed interiorly of the upstanding rod, and said leaf springs when unflexed, as in Fig. 7, are in facing, parallel relation to each other, as well as in parallel relation to said upstanding rods. Midportions of the leaf springs are secured, as at 35, to outer end portions of the upstanding rods, outer end portions 36 of said leaf springs extend to position above said upstanding rods, and inner end portions 37 of the leaf springs extend to position below the locations where secured to the upstanding rods. As disclosed, the lower ends of the inner end portions 37 of said leaf springs terminate in spaced relation to the elongated rectilinear bar 28, and all of the outer and inner end portions 36, 36, 37, 37 are of equal length. In effect, each of the elements 36, 36, 37, 37 is a separate leaf spring.

The free end of each of the outer and inner end portions of the leaf springs supports an attaching clip, each denoted 38. The attaching clips can be of ordinary or preferred construc-

tion. As disclosed, each attaching clip includes oppositely disposed gripping arms 39, 39 pivotally supported and urged toward each other by a tubular retainer 40. A type of attaching clip suitable to the purpose and now of commerce is disclosed very clearly in Fig. 8 of the drawing.

The target 12 is of sheet material. It may consist of any substance suitable to its purpose, such, for example, as paper, cardboard, leather, etc. The manner in which the target is retained in the frame 11 will be evident from Figs. 1 and 8 of the drawing. Attachment clips at the four corners of the target are releasably gripped thereon thus to retain said target in spread out and taut condition. The leaf springs 34 will be flexed toward each other, as in Fig. 1, when the holder is retaining a target. The exact positions of the attaching clips 38 relative to the upstanding rods 29, 29, when said attaching clips are retaining a target, will depend upon the size and shape of the target.

When the target holder is to be out of use, several of its parts can be disassembled, and other parts can be collapsed. That is to say, the adjustable post 10 can be removed from the elongated rectilinear bar 28 and the upper and lower telescoping elements 13 and 14 can be disjoined, and each of the upstanding rods 29, together with the leaf springs and the attaching clips carried thereby, can be swung, first outwardly and downwardly and then inwardly and upwardly, to position where adjacent the elongated rectilinear bar 28, as in Figs. 4, 5 and 6. When the target holder is to be put to use, its several parts can be very readily and easily assembled and set up.

What is claimed is:

1. In a holder for targets, an elongated bar, spaced apart, upright rods rigid with said elongated bar and extending from a single side thereof, attaching clips, and spaced apart spring members each having one of its ends secured to one of said upright rods in spaced relation to said elongated bar and its other end secured to one of said attaching clips.
2. In a holder for targets, an elongated bar, spaced apart, upright rods rigid with said elongated bar and extending from a single side thereof, attaching clips, and spaced apart leaf springs each having one of its ends secured to one of said upright rods in spaced relation to said elongated bar and its other end secured to one of said attaching clips.
3. In a holder for targets, an elongated bar, spaced apart, upright rods rigid with said elongated bar and extending from a single side thereof, attaching clips, and a pair of leaf springs supported upon each of said upright rods, each of said leaf springs having an inner end thereof secured to the corresponding upright rod in spaced relation to said elongated bar and an outer end thereof secured to one of said attaching clips.
4. In a holder for targets, an elongated bar, spaced apart, upright rods rigid with said elongated bar and extending from a single side thereof, attaching clips, and a pair of leaf springs supported upon each of said upright rods, each of said leaf springs having an inner end thereof secured to the corresponding upright rod in spaced relation to said elongated bar and an outer end thereof secured to one of said attaching clips, and the locations of securing all of the leaf springs and attaching clips to each other lying substantially in a single plane.
5. A holder for targets comprising a supporting post, an elongated bar extending transversely of and rigid with an upper portion of said sup-

porting post, upright rods rigid with said elongated bar and situated in spaced relation to said supporting post at opposite sides thereof, attaching clips, and spaced apart spring members each having one of its ends secured to one of said supporting rods and its other end secured to one of said attaching clips.

6. The combination as specified in claim 5 wherein said spring members are constituted as leaf springs.

7. A holder for targets comprising a supporting post, an elongated bar extending transversely of and detachably secured to an upper portion of said supporting post, upright rods secured to said elongated bar and situated in spaced relation to said supporting post at opposite sides thereof, spaced apart spring members upon each of said upright rods, and attaching clips secured to portions of said spring members in spaced relation to said upright rods.

8. The combination as specified in claim 7 wherein said spring members are constituted as leaf springs.

9. The combination as specified in claim 7 wherein said supporting post is constituted as upper and lower telescoping elements, and means for fastening said upper and lower telescoping elements in fixed relation to each other.

10. In a holder for targets, an elongated bar, spaced apart rods pivotally supported upon opposite ends of said elongated bar for swinging movement to upright position above and to collapsed position below the elongated bar, and means for limiting swinging movement of said spaced apart rods toward each other beyond upright position.

11. In a holder for targets, an elongated bar, spaced apart rods pivotally supported upon opposite ends of said elongated bar for upward and inward swinging movement to upright position above and downward and inward swinging movement to collapsed position below the elongated bar, means for limiting inward swinging movement of said spaced apart rods beyond upright position, leaf springs secured to the upright rods, and attaching clips secured to said leaf springs.
